TRAIN DIRECTION RESPONSIVE
APPARATUSEarl M. Allen, Swissvale, Pa., assignor to The
Union Switch & Signal Company, Swissvale,
Pa., a corporation of Pennsylvania

Application January 14, 1939, Serial No. 250,962

5 Claims. (Cl. 246—219)

My invention relates to train direction responsive apparatus for a stretch of single track railway, divided into two sections, over which traffic movements may normally be made in either direction.

One feature of my invention is the provision of railway traffic direction responsive means which responds in a characteristic manner to a train first entering the first of said sections, and which responds in a given different characteristic manner to a second train first entering the second of said sections while moving over said stretch in the opposite direction, regardless of whether or not the first train has entered the first section and then backs out after the second train enters the stretch.

I shall describe two forms of apparatus embodying my invention, and shall then point out the novel features thereof in claims.

20 In the accompanying drawing, Fig. 1 is a diagrammatic view showing one form of apparatus embodying my invention, in which there is provided, for a stretch of single track railway adjacent a switching yard, a given signal light which is retained in the unlighted condition when a first train moves over the single track in a given direction and which displays a flashing indication when a second train moves over the same stretch of track in the opposite direction, regardless of whether or not the first train has first entered the stretch and then backs out after the second train enters the stretch; and Fig. 2 is a diagrammatic view showing another form of apparatus embodying my invention, in which a stretch of single track railway intersected by a highway is provided with a crossing signal operated by a second train entering the stretch, regardless of whether or not a first train has entered the stretch from the opposite direction before the arrival of the second train and has then backed out of the stretch after arrival of the second train.

Similar reference characters refer to similar parts in each of the views.

45 Referring first to Fig. 1, a stretch of single track railway over which traffic movements can normally be made in either direction is shown adjacent a yard or switching track or group of such tracks designated by the reference character Y. The rails 1 and 1a of the stretch of single track are divided by means of insulated joints 3 to form two sections designated by the reference characters 1T and 2T, respectively. Each of these track sections is provided with a track circuit including a track battery 4 connected across the rails adjacent one end of the track section and a track relay, designated by the reference character R with a prefix corresponding to the reference character for the associated section, adjacent the other end of the section. A

third track relay, which may be called an auxiliary relay, designated by the reference character A2TR, is also provided for the section 2T. The terminals of relay A2TR are connected with rail 1a of section 2T on opposite sides of an insulated joint 5 at a location very close to joints 3 at signal 2 within the section. Relay A2TR is therefore in series with relay 2TR.

For governing traffic movements from left to right as shown in the drawing, which I shall assume to be the eastbound direction, a signal 1A is shown adjacent the west end of section 1T. A second signal, designated by the reference character 2, for governing westbound traffic movements is located adjacent the east end of section 1T. Each of these signals has a green lamp G, for directing traffic movements into section 1T, and a red or stop lamp R. A signal device designated by the reference character 1B is shown as a red lamp R, and is located adjacent signal 1A.

20 A slow release repeater relay, designated by the reference character 1—2TPR, is controlled by front contacts of relays 1TR and 2TR. A signal control relay designated by the reference character 1AHR, for controlling the lamps of signal 1A, is controlled by a front contact of relay 1—2TPR.

25 A slow release stick relay 1SR becomes energized when an eastbound train enters section 1T, and is retained in the energized condition while the train occupies section 1T and section 2T is unoccupied. A second stick relay 2SR becomes energized when the eastbound train enters section 2T and 1SR is energized. Both stick relays 35 1SR and 2SR are then retained in the energized condition while the eastbound train proceeds through section 2T.

30 A traffic direction responsive means, shown as a slow release relay 1BHR, is constantly energized when either a front contact of relay 1—2TPR is closed while sections 1T and 2T are unoccupied, or a front contact of relay 1SR is closed by an eastbound train. A slow release traffic responsive relay, designated by the reference character 1BHPR, becomes energized when relay 1BHR becomes deenergized. Then when relay 1BHPR is energized, relay 1BHR becomes energized by a circuit including a front contact of relay 1BHPR, and relay 1BHR, thus again becoming energized, in turn again deenergizes relay 1BHPR. This alternating operation of relays 1BHR and 1BHPR occurs when the circuit for normally energizing relay 1BHR is open at contacts 11 and 12 of relays 1—2TPR and 1SR, respectively.

35 Lamp R of signal device 1B is lighted by a circuit which includes a back contact of relay 1BHR. Hence lamp R of signal device 1B is unlighted when relay 1BHR is constantly energized,

and shows a flashing light when relays 1BHR and 1BHPR are alternately energized and de-energized.

Referring now to Fig. 2, a stretch of single track railway is shown intersected by a highway H. Rails 1 and 1a of the railway are divided by insulated joints 3 to form sections 3T and 4T. Sections 3T and 4T are provided with track circuits which are similar to the track circuit described for section 2T of Fig. 1, with auxiliary relays A2TR and A4TR connected with rail 1 of the corresponding sections around insulated joints 5 similarly to relay A2TR connected with section 2T but in this case connected to the rail 15 in the vicinity of the relay instead of the track battery.

A slow release interlocking relay designated by the reference character XR, having a first magnet *a* and a second magnet *b*, controls traffic direction responsive means shown as a signal device such as a highway crossing signal S. Magnets *a* and *b* are provided with pick-up circuits controlled by front contacts of relays 3TR and 4TR, respectively. Each of these magnets is provided with a stick circuit controlled by a back contact of the track relay and a front contact of the auxiliary relay for the section which controls the pick-up circuit for the other magnet.

In each of the views, the contacts operated by the various relays are identified by numbers, each such number having a distinguishing prefix from which it is separated by a dash when the contacts are shown apart from the relay by which they are operated. The prefix for each of these contact numbers comprises the reference character for the relay by which it is operated. For example, contact 1BHR-23, which controls lamp R of signal device 1B shown in Fig. 1, is identified by the number 23 separated by a dash from the prefix 1BHR which is the reference character for relay 1BHR by which this contact is operated.

Having described, in general, the arrangement and control of the various parts of the two forms of apparatus embodying my invention shown in the accompanying drawing, I shall now describe in detail the operation of the apparatus.

As shown in the drawing, all parts of the apparatus are in the normal condition, that is, the various track sections are unoccupied, and hence the track relays and auxiliary relays are energized; relays 1-2TPR, 1AHR and 1BHR shown in Fig. 1, and magnets *a* and *b* of interlocking relay XR shown in Fig. 2 are energized; relays 1SR, 2SR and 1BHPR shown in Fig. 1 are de-energized; lamp G of signal 1A and lamp R of signal 2 shown in Fig. 1 are lighted; and bell S shown in Fig. 2 is deenergized.

I shall first trace the operation of the form of apparatus shown in Fig. 1. With relays 1TR and 2TR energized, relay 1-2TPR is energized by a circuit passing from terminal B of a suitable source of current not shown in the drawing, through contacts 6 and 7 of relays 2TR and 1TR, respectively, and the winding of relay 1-2TPR to terminal C of the same source of current. With relay 1-2TPR energized, relay 1AHR is energized by its circuit including the front point of contact 8 of relay 1-2TPR. With relay 1AHR energized, the circuit for lamp G of signal 1A is closed, passing from terminal B, through the front point of contact 9 of relay 1AHR, and lamp G of signal 1A to terminal C. Also with relay 1-2TPR energized, lamp R of signal 2 is lighted by a circuit passing from terminal B, through the

front point of contact 1-2TPR-10, and lamp R of signal 2 to terminal C. Also, with relay 1-2TPR energized, relay 1BHR is energized by a circuit passing from terminal B, through contact 11 of relay 1-2TPR, back point of contact 13 of relay 1BHPR, and the winding of relay 1BHR to terminal C.

I shall assume that an eastbound train passes signal 1A and enters section 1T. Relay 1TR, upon becoming deenergized by the train in section 1T, permits its contact 7 to open at the front point and thereby deenergize relay 1-2TPR.

Relay 1-2TPR being of the slow releasing type, its contact 15 will remain closed at the front point long enough to permit a pick-up circuit for relay 1SR to energize this relay, this circuit passing from terminal B, through contact 6 of relay 2TR, back point of contact 7 of relay 1TR, front point of contact 15 of relay 1-2TPR, and winding of relay 1SR to terminal C. Relay 1SR, upon becoming energized, closes its contact 22, thereby completing a stick circuit which is the same as the pick-up circuit just traced except that it includes contact 22 of relay 1SR instead of the front point of contact 15 of relay 1-2TPR.

When contact 8 of relay 1-2TPR opens, relay 1AHR becomes deenergized, thereby opening the circuit previously described for lamp G of signal 1A and closing the circuit for lamp R of signal 1A passing from terminal B, through the back point of contact 9 of relay 1AHR, and lamp R of signal 1A to terminal C.

With relays 1TR and 1-2TPR deenergized, a second circuit is now complete for lighting lamp R of signal 2, this circuit passing from terminal B, through the back point of contact 1-2TPR-10, back point of contact 1TR-16, and lamp R of signal 2 to terminal C.

With relay 1SR energized, a second circuit is completed for energizing relay 1BHR, which is the same as the circuit previously traced except including contact 12 of relay 1SR instead of contact 11 of relay 1-2TPR.

When the eastbound train enters section 2T, both relays A2TR and 2TR become deenergized. With contact 19 of relay 1SR closed, and with relay A2TR deenergized, a pick-up circuit is completed for energizing relay 2SR, passing from terminal B, through contacts 18 and 19 of relays A2TR and 1SR, respectively, and the winding of relay 2SR to terminal C. On account of relay 2TR now being deenergized, the stick circuit previously traced for relay 1SR is open at contact 6 of relay 2TR, but relay 1SR, being of the slow release type, does not at once permit its front contacts 22 and 19 to open. Relay 2SR, upon becoming energized, closes its contact 20, thereby completing its stick circuit passing from terminal B, through contact 20 of relay 2SR, contact 19 of relay 1SR, and the winding of relay 2SR to terminal C. With relay 2SR energized and relay 1-2TPR deenergized, a second stick circuit is now completed for relay 1SR, passing from terminal B, through contact 21 of relay 2SR, back point of contact 15 of relay 1-2TPR, and contact 22 of relay 1SR to terminal C. Relays 1SR and 2SR will now remain energized, by these stick circuits which are controlled by each other, as long as relay 1-2TPR remains de-energized.

When the eastbound train leaves section 1T, permitting relay 1TR to become energized, lamp R of signal 2 will be energized by a third circuit passing from terminal B, through the back point

of contact 1-2TPR-10, the front point of contact 1TR-16, the front point of contact ISR-17, and lamp R of signal 2 to terminal C.

When the eastbound train leaves section 2T, relay 2TR will again become energized, completing the return of the apparatus to the normal condition.

I shall next assume that, with all parts of the apparatus again in the normal condition, a westbound train enters section 2T, deenergizing relay 2TR, which in turn, by the opening of contact 6, deenergizes relay 1-2TPR. Relay 1SR can not now be energized by its pick-up circuit, previously traced, since contact 6 of relay 2TR is open.

With relay 1-2TPR deenergized, relay 1AHR will become deenergized and lamp R of signal 1A will become lighted as before. Also, with relay 1-2TPR deenergized, a circuit will be completed for lighting lamp G of signal 2, this circuit passing from terminal B, through the back point of contact 1-2TPR-10, front point of contact 1TR-16, back point of contact ISR-17, and lamp G of signal 2 to terminal C.

With relays 1-2TPR and ISR deenergized, relay 1BHR will become deenergized, thereby completing a circuit for energizing relay 1BHPR, this circuit passing from terminal B, through contact 14 of relay 1BHR, and the winding of relay 1BHPR to terminal C. Also, with relay 1BHR deenergized, a circuit will be completed for lighting lamp R of signal device 1B, this circuit passing from terminal B, through contact 1BHR-23, and lamp R of signal device 1B to terminal C. When relay 1BHPR becomes energized, a circuit is completed for energizing relay 1BHR, passing from terminal B, through the front point of contact 13 of relay 1BHPR, and the winding of relay 1BHR to terminal C. With relay 1BHR again energized, relay 1BHPR again becomes deenergized. It follows that relays 1BHR and 1BHPR will be alternately energized and deenergized as long as the circuits first traced for relay 1BHR through contacts 11 and 12 of relays 1-2TPR and ISR, respectively, remain open.

With relay 1BHR alternately energized and deenergized, lamp R of signal device 1B will be controlled by contact 1BHR-23 to display a flashing red indication. Trainmen in the vicinity of track Y will, therefore, now know that a westbound train is approaching, and hence no trains will leave track Y until the westbound train has passed.

I shall now assume that a train is making switching movements at track or yard Y, and that it enters section 1T, causing the apparatus to be arranged as previously described for an eastbound train entering section 1T. I shall further assume that while section 1T is occupied, a westbound train enters section 2T, thereby deenergizing relay 2TR and ISR. Relay A2TR will remain energized until the westbound train passes insulated joint 5 associated with relay A2TR, and hence relay 2SR does not become energized when the westbound train enters section 2T. With relay 2TR deenergized, the first stick circuit traced for relay 1SR is now open, and hence relay 1SR becomes deenergized.

With both relays ISR and 1-2TPR deenergized, lamp R of signal device 1B will be controlled to display a flashing indication as previously described. The trainman in charge of the switching movements at yard Y will now know that a westbound train is approaching, and will therefore move the train which occupies

section 1T into yard Y to get into the clear and permit the westbound train to pass. As soon as the switching train clears section 1T, lamp G of signal 2 will become lighted by the circuit previously traced, and the westbound train will then proceed through section 1T.

I shall now trace the operation of the form of apparatus shown in Fig. 2. The circuit by which magnet a is energized passes from terminal B, through the front point of contact 24 of relay 3TR, and the winding of magnet a to terminal C. Magnet b is energized by a similar circuit including the front point of contact 24 of relay 4TR.

I shall assume that an eastbound train enters section 3T, deenergizing relay 3TR and thereby opening the pick-up circuit traced for magnet a. With magnet a deenergized, front contact 27 controlled by this magnet will become opened, and contact 29 also controlled by this magnet will become closed. With contact 29 closed, a circuit will be completed for energizing crossing signal S, passing from terminal B, through contact 29 controlled by magnet a, and through the mechanism of signal S to terminal C. Signal S will therefore be operated while the eastbound train is approaching highway crossing H.

When the eastbound train passes the insulated joints at highway H, relay 4TR becomes deenergized, causing magnet b to become deenergized. However, due to a well-known characteristic of interlocking relays, front contact 26, known as the flagman type of contact, will not open on account of magnet a having been deenergized before magnet b. Also, contact 28 of magnet b will not close.

When the train leaves section 3T, magnet a will again become energized by its circuit previously traced, causing its contact 29 to open and thereby discontinue the operation of signal S. Signal S will then remain deenergized as the eastbound train proceeds through section 4T.

I shall next again assume that an eastbound train enters section 3T, causing signal S to be operated as previously described. I shall further assume that while the eastbound train occupies section 3T, a westbound train enters section 4T. With the westbound train on section 4T, magnet b will become deenergized on account of the opening of contact 24 of relay 4TR at its front point. However, for the reason previously given, contact 26 of magnet b will not open, and contact 28 of this magnet will not close. I shall still further assume that the eastbound train now backs out of section 3T.

When the eastbound train, in backing out, vacates the portion of section 3T which is east of insulated joint 5, relay A3TR will become energized, thereby completing a stick circuit for magnet b, passing from terminal B, through the back point of contact 24 of relay 3TR, contact 25 of relay A3TR, flagman contact 26 controlled by magnet b, and the winding of magnet b to terminal C. With magnet b thus energized, the mechanism operated by magnet b will be removed from interlocking engagement with the mechanism operated by magnet a.

When the eastbound train leaves section 3T, in backing out, magnet a will again become energized by its pick-up circuit, and the stick circuit for magnet b, traced through the back point of contact 24 of relay 3TR, will become opened. Magnet b will therefore become deenergized, but, on account of its slow release characteristic, will not permit its contact 26 to open and its con-

tact 28 to close until after magnet a has lifted its contacts. Signal S will therefore now be operated by a second circuit, including contact 28 of magnet b, until the westbound train leaves section 4T.

From the foregoing description and the accompanying drawing, it follows that in one form of apparatus embodying my invention, I have provided railway traffic direction responsive means for use with a single track railway for controlling a signal device which remains deenergized when a train is making switching movements such, for example, as in a railway yard or at a switch in an A. P. B. signaling system, 10 but becomes energized when a train approaches from the opposite direction. In a second form of apparatus embodying my invention, I have provided a control arrangement for a highway crossing signal so controlled that, if a train approaching a highway crossing stops and backs away from the crossing while a second train is approaching the crossing from the opposite direction, the crossing signal will continue to be operated by the second train after the first train 20 has vacated its controlling track section. 25

Although I have herein shown and described only two forms of apparatus embodying my invention, it is understood that various changes and modifications may be made therein within 30 the scope of the appended claims without departing from the spirit and scope of my invention.

Having thus described my invention, what I claim is:

1. In combination, a stretch of railway track 35 divided into a first and a second section, a signal device, means responsive to a train moving over said first and second sections in a direction in which it enters said first section before entering said second section for retaining said signal device in the deenergized condition, and means responsive 40 to a second train moving over said track in the opposite direction for energizing said signal device regardless of whether or not said first section is already occupied at the time said second 45 train enters said second section.

2. In combination, a stretch of railway track divided into a first and a second section, a track circuit for said second section including a track relay connected across the rails of said second 50 section as well as a second relay connected around an insulated point in one side of said track section in series with said track relay, a signal device, means including said first and second relays controlled by a train moving over said first and second 55 sections in a direction in which it enters said first section before entering said second section for retaining said signal in the deenergized condition while said train occupies said second section after leaving said first section, and means including said first and second relays controlled 60 by a train moving in the opposite direction over said stretch for energizing said signal device while said train occupies said second section.

3. In combination, a stretch of railway track 65 divided into a first and a second section, train detecting means operable in response to a train on said stretch, a first relay, a second relay, means controlled by a train entering said stretch in a given direction for energizing said first relay 70 when said train enters said first section and for

energizing said second relay when said train enters said second section, means controlled by said second relay for then retaining said first relay in the energized condition while said second section is occupied, means controlled by said first 5 relay for then retaining said second relay energized as long as said first relay remains energized, a signal device, and means controlled by said first relay and by said train detecting means for retaining said signal device in the deenergized 10 condition while a train moves over said stretch in said given direction and for energizing said signal device while a train moves over said stretch in the opposite direction.

4. In combination, a stretch of railway track divided into a first and a second section, a track circuit for said first section including a first track relay, a track circuit for said second section including a second track relay connected across the rails adjacent one end of said section and also including a third track relay connected with an intermediate portion of said section in series with said second track relay, a slow release repeater relay, a circuit for energizing said repeater relay controlled by front contacts of said first and second 20 track relays, a first slow release stick relay, a pick-up circuit for said first slow release stick relay controlled by a back contact of said first track relay and by front contacts of said second track relay and said repeater relay, a first stick 25 circuit for said first slow release stick relay controlled by a back contact of said first track relay and a front contact of said second track relay, a second stick relay, a pick-up circuit for said second track relay controlled by a front contact of 30 said first slow release stick relay and a back contact of said third track relay, a stick circuit for said second stick relay controlled by a front contact of said first slow release stick relay, a second stick circuit for said first slow release stick 35 relay controlled by a front contact of said second stick relay and a back contact of said repeater relay, a signal device, and means controlled by front contacts of said first stick relay and said repeater relay for controlling said signal device. 40

5. In combination, a stretch of railway track divided into a first and a second section, a track circuit for said first section including a first track relay, a track circuit for said second section including a second track relay connected across the rails adjacent one end of said section and also including a third track relay connected with an intermediate portion of said section in series with said second track relay, a stick relay, means controlled by said first and second track relays 55 for energizing said stick relay when said first track relay becomes deenergized while said second track relay is energized, means for then retaining said stick relay in the energized condition while said first track relay is deenergized and said second track relay is energized, other means controlled by said second and third track relays in the deenergized condition for continuing to retain said stick relay in the energized condition, a signal device, and means controlled by said first and second track relays or by said stick relay in the energized condition for controlling said signal device. 60
